UNITED STATES PATENT OFFICE

FRANCIS P. TIKALSKY, OF LA GRANGE, ILLINOIS, ASSIGNOR TO WESTERN ELECTRIC COMPANY, INCORPORATED, OF NEW YORK, N. Y., A CORPORATION OF NEW YORK

DIE CASTING MACHINE

Application filed January 9, 1930. Serial No. 419,660.

This invention relates to die casting machines, and more particularly to casting pumps forming a part of such machines.

In certain types of machines for casting metal in metallic molds or dies, a movable pump or gooseneck is provided which, by the operation of suitable actuating mechanism, is dipped into a pot of molten metal and thereby filled with molten metal to be cast, and the pump or gooseneck is then moved into casting position, where a metal-ejecting nozzle on the pump connects with a gland or sprue which leads to the dies. An air-receiving nozzle on the pump simultaneously

connects with a gland which communicates with a source of compressed air, the compressed air forcing the molten metal from the pump into the sprue and thence to the dies. It is essential to the efficient operation of the pump that both nozzles register simultaneously and accurately with their respective glands in spite of expansion and contraction of the parts due to changing temperatures.

An object of this invention is to provide a casting device for a die casting machine which may be accurately aligned with its associated parts to insure proper movement of the molten metal to the die.

In one embodiment of the invention, an air-receiving nozzle is mounted eccentrically upon a hollow threaded shank which engages in a correspondingly threaded bore in the pump in such manner that the distance between the air-receiving nozzle and the metal-ejecting nozzle may be increased or decreased by rotating the shank relative to the bore.

Further objects of the invention will be apparent from the following description, taken in connection with the appended drawings, in which

Fig. 1 is a fragmentary longitudinal view, partly in section, of a die casting machine embodying the invention, and

Fig. 2 is an enlarged sectional view of the air-receiving nozzle.

The die casting machine shown in the drawings comprises a pump or gooseneck 10 which is shown in casting position relative to a stationary bolster plate 11 to which a

stationary die section 12 is secured, a movable die section 13 being shown in cooperative relation thereto. A supply of molten metal 14 to be cast is contained in a melting pot 15, into which the pump 10 is dipped and from which it is raised by suitable actuating means of known construction comprising a horizontal bracket 16 which is secured to the pump. The bracket 16 is supported by mechanism which includes a link 17 pivoted to an adjusting member 18 which is in turn pivoted to a bracket 19 fixed to the machine frame and adjustable by means of set screws 20.

The pump 10 is of a gooseneck type and is provided with a chamber 21 for molten metal, and with a metal-ejecting nozzle 22 adapted to be dipped below the level of the metal 14 so that the chamber will fill by gravity through the nozzle. The nozzle is designed to register, when the pump is in a casting position, with a gland 24, of any suitable construction, which constitutes the sprue leading to the dies formed in die sections 12 and 13. The upper portion 23 of the pump comprises an air conduit 26 which communicates with chamber 21 and terminates in an enlarged threaded bore 25 in which the correspondingly threaded tubular shank 28 of an air-receiving nozzle 30 engages, the shank 28 being eccentrically related to the bore of the nozzle. Nozzle 30 is shaped to seat in a recess or nipple 32 which is formed in the upper portion of plate 11, and when so seated registers with an air duct 34 which is connected to any suitable source of compressed air (not shown).

In order to facilitate rotation of the nozzle 30 relative to bore 25, the nozzle is provided with a hexagonal collar 36 adapted to receive a wrench or other rotating means, and it will be readily understood that rotation of nozzle 30 will result in increasing or decreasing the distance between the air-receiving nozzle 30 and the metal-ejecting nozzle 22, thereby compensating for expansion and contraction of the pump 10 and its associated parts due to temperature changes. Such adjustment may be made during the operation of the machine, and enables the operator to maintain the registry of nozzles

22 and 30 with their respective glands at all times, even though the temperature of the parts may rise during the progress of the casting or because of different metals being 5 cast in the machine at different times. It will thus be seen that the eccentricity of the nozzle 30 permits adjustment not only in a vertical direction but also laterally of the axis of the nozzle, while the threaded engagement 10 of shank 28 with the bore 25 permits adjustment longitudinally of the nozzle; and since these adjustments may be made concurrently, the nozzle may be said to be adjustable in three planes. The nozzle 30 is held in its 15 adjusted position by means of a lock-nut 38 which is threaded on the shank 28.

In the operation of the die casting machine, the metal-ejecting nozzle 22 is accurately alined with gland 24 by loosening one of the 20 screws 20 and tightening the other to raise or lower the pump 10 relative to the frame of the machine. Nozzle 30 is then adjusted by loosening lock nut 38 and rotating the nozzle 30 until it registers with gland 32, whereupon 25 the lock nut is tightened to hold the nozzle 30 in its adjusted position.

While the invention has been described with particular reference to a specific embodiment thereof, it may be embodied in various 30 other forms, and is not limited except by the language of the following claims. Thus, it will be apparent that the nipple 32 may be made adjustable rather than the nozzle 30, in order to provide proper registry of the 35 nozzles, as well as such other changes as fall within the spirit of the invention.

What is claimed is:

1. In a die casting machine, a movable pneumatic pump, a stationary member designed to supply motive fluid to the pump, and a motive fluid receiving member comprising a nozzle portion and a tubular portion eccentrically related to the nozzle portion to permit adjustment of the nozzle toward and away from the stationary member.
2. In a die casting machine, a movable pneumatic pump, a member designed to supply motive fluid thereto, and a motive fluid receiving member comprising a nozzle portion and a tubular portion eccentrically related to the nozzle portion threadedly engaging the pump to permit adjustment of the nozzle portion toward and away from the first mentioned member.
3. In a pneumatic pump for a die casting machine, a member for receiving motive fluid comprising a nozzle portion and a tubular portion eccentrically related to the nozzle portion and threaded into a bore in the pump to permit adjustment of the nozzle relative to the pump in three planes.
4. In a pneumatic pump for a die casting machine, a metal-ejecting nozzle designed to register with a stationary member, and an air-receiving member designed to register

with an air-supplying member, said air-receiving member comprising a nozzle portion and a tubular portion eccentrically related to the nozzle portion and threadedly engaging the pump.

In witness whereof, I hereunto subscribe my name this 31st day of December A. D., 1929.

FRANCIS P. TIKALSKY.
